FLORAL WASH SPONGE

Albert Mosheim, 10 N. Ridgewood Road,
South Orange, N.J.

Filed June 30, 1961, Ser. No. 65,779

Term of patent 14 years

(Cl. D9—2)

FIG. 1.

FIG. 2.

FIG. 3.

FIG. 1 is a plan view of a floral wash sponge embodying my new design showing one face thereof;

FIG. 2 is a plan view showing the opposite face from that shown in FIG. 1; and

FIG. 3 is a side elevation thereof.

I claim:

The ornamental design for floral wash sponge, substantially as shown.
